CONTAINER FORMING APPARATUS

Charles E. Palmer, Glenview, Ill., assignor, by
mesne assignments, to Package Machinery
Company, East Longmeadow, Mass., a corpora-
tion of Massachusetts

Application October 9, 1948, Serial No. 53,693

6 Claims. (Cl. 93—51)

1

This application is concerned with mechanism for forming a paperboard container which may be in the form of a tray (i. e., a box without a cover) or, a box having a cover hinged to one of its sides.

The main objects of the invention are to provide apparatus of a relatively simple character which will efficiently fold a preformed blank into container form; to provide such apparatus which will be operative to effect engagement of locking elements provided as a part of the container structure to lock the same in setup condition; and, in general, it is the object of this invention to provide an improved container forming apparatus of the character indicated.

Other objects and advantages of the invention will be understood by reference to the following specification and accompanying drawings (3 sheets) wherein there is illustrated apparatus embodying a selected form of the invention, and a blank which the illustrated apparatus is adapted to fold into container form.

In the drawings:

Fig. 1 is a front elevation, portions being, however, shown in section to more clearly illustrate certain details;

Fig. 2 is a section corresponding in part to Fig. 1, but showing certain parts in changed positions;

Fig. 3 is a section approximately on the plane represented by the line 3—3 of Fig. 2;

Figs. 4 and 5 are sectional illustrations similar to Fig. 2 but showing successively changed positions of the parts;

Fig. 6 is an elevation of certain operating linkage appearing at the left-hand end of Fig. 1;

Fig. 7 is a perspective illustrating a paperboard blank which is adapted to be folded and locked in tray form by the illustrated apparatus;

Fig. 8 is a plan of the die plate portion of the apparatus, and

Fig. 9 is a section on the plane represented approximately by the line 9—9 of Fig. 1.

The blank illustrated in Fig. 7 is of paperboard having a central bottom panel 1, opposite end wall panels 2 and 3, and opposite side wall panels 4 and 5. The end panels 2 and 3 are extended so as to also provide inner end wall panels 6 and 7 respectively and bottom panels 8 and 9 respectively.

The side wall panels 4 and 5 are respectively integrally interconnected at their ends to the adjacent ends of the end panels 2 and 3 by corner gussets 10. These corner gussets are connected to the side and end wall panels by fold lines or

2

creases and they are provided with fold lines 11 extending diagonally outwardly from the respective corners of the bottom panel 1. The side wall panels 4 and 5 also have extension sections 12 and 13 respectively which are refolded over the inside faces of the side walls, and adhesively or otherwise secured thereto. The inner side wall sections 12 and 13 may be folded and glued in place as a step in the production of the blank so that the blanks are delivered to the container-forming apparatus in the condition illustrated in Fig. 7.

Blanks such as shown in Fig. 7, are folded into tray-forming condition by first folding the two 15 ply side walls upwardly, folding the end wall panels 2 and 3 upwardly, the corner gussets 10 being folded inwardly upon themselves and caused to lie against the inside faces of the end panels 2 and 3. In the construction shown, the side walls are intended to be folded to perpendicular relation to the bottom panel. The end wall extensions 6 and 7 are then folded downwardly into inwardly overlapping relation to the inside of the end walls 2 and 3 and inwardly over the folded gussets 10 which are accordingly housed between the end wall panels 2 and 6 at one end and the end wall panels 3 and 7 at the other end of the tray. The end wall extensions 8 and 9 are folded relative to the panels 6 and 7 to lie flat against the bottom panel adjacent the ends of the tray. As indicated in Fig. 7, the end wall panels 6 and 8 at one end of the blank and the end wall panels 7 and 9 at the other end thereof are extended slightly at the ends of the panels 35 so as to provide lip-like extensions which are adapted to fit behind the ends of the inner side wall panels 12 and 13 and under the lower edges thereof to more or less lock the tray in its set-up condition.

40 The apparatus for forming blanks, such as shown in Fig. 7 into trays as described, comprises a mandrel 14 and a die plate structure 15 through which the mandrel is passed to fold the blank around the mandrel.

45 The mandrel may be of any suitable construction, the length and width of the mandrel corresponding substantially to the inside length and width of the tray to be formed. In this instance, the mandrel has a bottom plate 16, end plates 50 17, 17 and side plates 18, 18 (see Figs. 1 and 9). These parts are suitably formed as an integral unit or as separate units rigidly united by welding or otherwise. The mandrel so formed is carried by a rod 19 which is vertically reciprocatably 55 mounted in any suitable manner. No invention

is claimed in respect of the details of this mounting wherefor such details are not herein illustrated. They may be in accordance with any known receptacle forming machine embodying a reciprocatable mandrel structure.

The die structure 15 comprises a main die plate 20 which has a central well or opening 21 through which the mandrel 14 may pass. The die plate may actually consist of a pair of bars as is best indicated in Figs. 8 and 9 which are spaced apart a distance substantially corresponding to the outside width of the receptacle to be formed, said width being greater than the corresponding width of the mandrel by an amount only slightly greater than the thickness 15 of the side walls so as to provide room for said side walls between the sides 18, 18 of the mandrel and the side edges 22, 22 of the die plate opening. These die plate edges 22, 22 are the side wall forming edges of the die plate and serve, in cooperation with the mandrel, to fold the side walls of the blank upwardly over the sides of the mandrel as an incident to the movement of the latter downwardly through the die plate opening.

The die plate 20 may, of course, be in the form of a single or unitary plate having the opening 21 cut therein and whether made of separate bars or a single plate, it is of course suitably supported by a supporting frame structure which is not herein illustrated. Such supporting frame may include parts on which the end portions of the die plate rest.

A carton blank is initially delivered into position over the die plate with the bottom panel 1 properly registered with the die plate opening 22. Suitable gauges indicated at 23 are provided for facilitating proper positioning of the blank.

The first portion of the travel of the mandrel 14 downwardly through the die plate opening 21 causes the side wall panels 4 and 12 at one side and 5 and 13 at the opposite side to be folded nearly to right angular upwardly extending relation to the bottom panel 1 as appears in Figs. 2 and 3. As best shown in Fig. 3, the die plate opening is preferably of such width that the side walls will remain in slightly outwardly inclined position rather than being folded to full right angular position. When the side wall panels are folded upwardly as indicated, the corner gussets 10 at each end of each side wall are also folded upwardly by the said folding edges 22 of the die plate.

End wall folders comprising blocks or plate-like elements 24 are disposed at a level somewhat below the level of the die plate 20, said end folders being bolted as shown to brackets 25, 25 which traverse the die plate opening and are anchored at their ends to the respective overlying portions of the die plate or die plate bars 20. The brackets 25 bridge the opening in the die plate 20 and have central portions thereof offset downwardly from the plane of said die plate 20 to support the folder blocks 24 at the illustrated downwardly spaced level with reference to the plane of the die plate 20.

The folders 24 have inner ends 26 disposed in such relation to the ends of the mandrel that as the mandrel descends between said edges 26 the end wall panels 2 and 3 will be folded upwardly over the ends 17, 17 of the mandrel.

The corner gussets 10 are folded upon themselves on their diagonal fold lines 11 as an incident to the folding of the end walls 2 and 3.

to upright position. To facilitate such automatic folding of the gussets, they are initially buckled inwardly along their said diagonal fold lines 11, 11. Such initial breaking or buckling of the gussets on the fold lines 11 is effected by means of pins, such as represented at 27, which are seated in and project from the folding edges 22 of the die plate 20. The projecting pins 27 are so located in said die plate edges as to engage the gussets 10 in alignment with the diagonal fold lines 11 therein when the side walls are folded upwardly as shown in Fig. 3. These projecting pins extend inwardly beyond the planes of the respective folding edges 22 as shown in Fig. 3 and are therefore operative to fold the central portions of said gussets inwardly beyond the planes of the initially folded side walls. The normal resiliency of the paperboard or the normal resistance thereof to being folded upwardly as shown, prevents the side wall panels from following the gussets inwardly and enables the projecting pins 27 to effect said buckling.

Continued downward movement of the mandrel 14 from the position represented in Figs. 2 and 3 serves to effect folding of the end walls 2 and 3 as already explained and incidentally thereto, folding of the corner gussets 10 upon themselves and inwardly into face to face relation to the respective end walls 2 and 3. In Fig. 4, the receptacle is shown in the lowest position to which it is carried on the mandrel 14, the mandrel having been withdrawn, leaving the receptacle with its end wall extensions 6 and 8 at one end and 7 and 9 at its other end extending upwardly in continuation of the folded end walls 2 and 3 respectively.

For holding the side walls in upwardly folded position during the movement of the receptacle downwardly from the die plate 20, there are provided side wall holding plates or flanges 28 which depend from the folding edges 22 of the die plate 20. These side wall holders 28 may be in the form of angle brackets having horizontal flanges suitably bolted to the die plate 20 as indicated at 29. The inside faces of the holders 28 have upper portions 30 which are recessed or offset outwardly from the folding edges 22 (see Fig. 3) and disposed at outwardly flaring angles to form a funnel-like entrance for guiding the receptacle into the space between the holders and for completing the folding of the side walls 4 and 5 from the slightly outwardly flaring position shown in Fig. 3 to substantially perpendicular relation to the bottom panel of the receptacle. As shown in Figs. 3 and 9, the inside faces of the holders 28 immediately below the flaring mouth portions 30 are disposed somewhat closer together than the folding edges 22 of the die plate, the spacing of these face portions being made in accordance with the outside width of the receptacle to be formed. As shown in Fig. 9, the lower portions of the inside faces of the holders 28 are again slightly recessed by the provision of angularly disposed outwardly offset face portions 31 which provide recesses into which the side walls of the receptacle may spring outwardly. Horizontal shoulders 32 formed in the holders 28 at the upper ends of the recessed faces 31, constitute abutments which are engaged by the upper edges of the receptacle side walls to prevent the receptacle from following the mandrel upwardly out of the die structure when the mandrel is retracted.

The end folders 24 are so spaced from each

other that they operate to fold the end walls 2 and 3 and the respective extensions thereof to substantially perpendicular relation to the bottom panel 1 of the receptacle. The brackets 25 which support said end folders are spaced outwardly from the planes of the receptacle end walls and rotatably support folders 33, 33 which are initially disposed in substantially vertical position as shown in Figs. 1 and 4. Also as shown in these figures, these folders 33 are located beneath portions of the folders 24 which project toward each other from the respective supporting brackets 25. These folders 33 are carried by bars 34 which have aligned end portions 35 offset from the normal axis of the bars and suitably journaled in bearing brackets or bosses indicated at 36 secured to or formed on the brackets 25 outwardly of the side wall holders 28. The axis of each mounting shaft 35 is substantially in register with the fold line between the side wall 2 or 3 and its extension 6 or 7, so that the folders 33 are rocked about an axis substantially coinciding with the lines on which the extensions 6 and 7 are folded.

After the mandrel has been retracted, the folders 33 are rocked substantially 180° from their initial positions as shown in Fig. 4 to their folding positions substantially as shown in Fig. 5. Suitable allowance may, of course, be made in the positioning of the operative face of the folders 33 for the thickness of the paper stock of the blank which is folded and for the thickness of the folded gussets 10 over which the end wall extensions are folded as shown in Fig. 5.

Folding movement may be imparted to the folders 33 by any suitable means. However, it is convenient and economical to effect this movement automatically as an incident to the retraction of the mandrel 18. To that end a cross arm 37 is secured to the mandrel post 19 and connecting rods 38, 38 have their upper ends connected to the opposite ends of the cross arm by means of pins 39 secured to the cross arm and slotted extensions 40 formed on or secured to said connecting rods 38. The lower ends of said connecting rods are screw threaded, as indicated at 41 (Fig. 6) and suitable eye end pieces 42 are screwed onto said threaded rod ends. Lock nuts 43 may be provided for locking the eye ends 42 in selected position of adjustment on the rods. The lower ends of the connecting rods are connected by means of pivot pins 44 to the free ends of rock arms 45 which are suitably pivotally mounted as indicated at 46 on the outside of one of the side wall holders 28 (see Fig. 9).

The free ends of the arms 45 are connected by links 47 to the free ends of rock arms 48 which are pinned, as indicated at 49 or otherwise secured to an extension of one of the pivot shafts 35 of each of the folders 33. As shown, the associated arms 45 and 48 are arranged in substantially parallel relationship with their lengths extending substantially perpendicularly from a plane or line passing through the pivot axes of both arms when the folders 33 are in their initial or open position.

The rock arms 48 are so much shorter than the rock arm 45 that 90° of rocking movement imparted to the longer rock arm 45 will be transformed into substantially 180° of rocking movement of the shorter rock arm 48 whereby the folder 33 will be correspondingly rocked 180°.

As already explained, the end folders 33 are in their upwardly extending positions as shown in Figs. 1 and 4 when the mandrel 14 is lowered

to the position in which it would leave a receptacle or tray in the position shown in Fig. 4. During the first portion of the upward or reTRACTING movement of the mandrel 14 the cross arm pins 39 move upwardly in the slotted ends 40 of the connecting rods without imparting upward movement to said rods. During this time the rods are held in their lowered positions as shown in Fig. 1, by suitable spring means which may be typified by springs so stretched between portions of the connecting rods 38 and conveniently accessible portions of the die plate structure or other stationary parts of the apparatus. As soon as the cross arm pins 39 reach the upper ends of the slotted connecting rod portions 40, the latter will be moved upwardly against the tension of the springs 50 to thereby impart upward rocking movement to the arms 45 and upward and inward rocking movement to the shorter arms 48. Such movement of the arms 48 is, of course, transmitted to the respective folder supporting bars 34 so that the folders 33 are rocked inwardly and downwardly to fold the upstanding end wall extensions 6 and 7 as shown in Figs. 4 and 5. When the end wall extensions are folded to the position shown in Fig. 5, they will be locked in that position by engagement of their projecting end portions with the ends of the inner plies 12 and 13 of the side walls.

Incident to the folding of said end wall plies 6 and 7 inwardly and downwardly, the extensions 8 and 9 will also be folded inwardly over the bottom wall of the receptacle. This occurs automatically because the plies 6 and 7 are of the same depth as the end walls 2 and 3 and the folders 33 are of such depth that said extensions will necessarily be folded under said folders by engagement with the bottom panel 1 as shown in Fig. 5.

When the mandrel starts its next downward movement, the springs 50 serve to cause the connecting rods 38 to move downwardly in unison with the mandrel. Before the mandrel enters the zone of operation of the end folders 33 in the die structure, the end folders will thereby be automatically returned to their initial, upwardly extending positions as shown in Figs. 1 and 4. Then during the final portion of the downward movement of the mandrel in the die structure, the cross arm pins 39 will move idly along the slots in the connecting rod portions 40 while the said connecting rods and end folders remain stationary. Upon retraction of the mandrel, the end folding operation again occurs as already explained.

By actuating the end folders 33 from the mandrel in the manner explained, proper timing of the folder operation is easily attained and when once attained requires no adjustment or care to maintain the required operating relationships. It is, of course, possible to actuate the folders 33 by cam mechanism or by electrically energized means, such devices being of course suitably timed with reference to the travel of the mandrel. The illustrated arrangement is, however, preferred because of its comparative simplicity and certainty of operation. Various other changes may be made in the described structure while retaining the principles of the invention.

I claim:

1. Apparatus for folding into carton form, a blank having a bottom panel, two relatively angularly disposed pairs of side wall forming panels, and end extensions on the free edges of one of

said pairs of wall panels, comprising a die structure, a reciprocally mounted mandrel, means for effecting reciprocation of said mandrel in operative relation to said die structure to thereby move said mandrel through said die structure to press said blank through the die structure, said mandrel and die structure having cooperating parts operative as an incident to the movement of the mandrel and blank through said die structure to fold the wall panels of the blank to angular, container wall forming relation to the bottom panel of the blank, movable folders in said die structure for engaging the outer faces of said wall extensions and folding the same inwardly over the inside of the respective walls from which they extend, and actuating mechanism for said folders, said actuating mechanism comprising a member movably mounted on said die structure, and means operatively connecting said part to said mandrel for actuation as an incident to retraction of said mandrel from said die structure.

2. Apparatus for folding into carton form, a blank having a bottom panel, two relatively angularly disposed pairs of side wall forming panels, and end extensions on the free edges of one of said pairs of wall panels, comprising a die structure and a reciprocating mandrel movable through said die structure to press said blank through the die structure, said mandrel and die structure having cooperating parts operative as an incident to the movement of the mandrel and blank through said die structure to fold the wall panels of the blank to angular, container wall forming relation to the bottom panel of the blank, folders pivotally mounted in said die structure for rotary movement through an arc of approximately 180° for engaging the outer faces of said wall extensions and folding said extensions inwardly over the inside of the respective walls from which they extend, and actuating mechanism for said folders comprising rock arms rigid with said folders, elongated rock arms respectively associated with said first mentioned rock arms, links interconnecting the free ends of said associated rock arms, connecting rods each having an end pivoted to one of said elongated rock arms and its other end provided with a pin and slot connection to said mandrel, and spring means resiliently holding said folders in starting position, the arrangement being such that as an incident to a terminal portion of the retractive movement of the mandrel, said elongated rock arm will be rocked through an arc of approximately 90°, said elongated rock arm being of such length relative to its associated rock arm that the 90° of movement imparted to the elongated rock arm will be transformed into substantially 180° of movement of its associated arm and the folder connected thereto.

3. Apparatus for folding into carton form, a blank having a bottom panel, two relatively angularly disposed pairs of side wall forming panels, and end extensions on the free edges of one of said pairs of wall panels, comprising a die structure and a reciprocating mandrel movable through said die structure to press said blank through the die structure, said mandrel and die structure having cooperating parts operative as an incident to the movement of the mandrel and blank through said die structure to fold the wall panels of the blank to angular, container wall forming relation to the bottom panel of the blank, folders pivotally mounted in said die structure for rotary movement through an arc of approximately 180° for engaging the

outer faces of said wall extensions and folding said extensions inwardly over the inside of the respective walls from which they extend, and actuating mechanism for said folders comprising 5 rock arms rigid with said folders, elongated rock arms associated with and in substantially parallel relation to said first mentioned rock arms, links interconnecting the free ends of said associated rock arms, connecting rods each having 10 an end pivoted to one of said elongated rock arms and its other end provided with a pin and slot connection to said mandrel, and spring means resiliently holding said folders in starting position, the arrangement being such that as an 15 incident to a terminal portion of the retractive movement of the mandrel, said elongated rock arm will be rocked through an arc of approximately 90°, said elongated rock arm being of such length relative to its associated rock arm that the 90° of movement imparted to the elongated rock arm will be transformed into substantially 180° of movement of its associated arm and the folder connected thereto.

4. Apparatus for folding into container form, a blank having a bottom panel and two relatively angularly disposed pairs of side wall forming panels, comprising a die structure and a mandrel movable through said die structure to press said blank through said die structure, said mandrel and die structure having cooperating parts operative as an incident to the movement of the mandrel and blank through said die structure, to fold the wall panels of the blank to angular wall forming relation to the bottom panel of the blank, said die structure comprising a spaced pair of die bars providing a pair of spaced edges which constitute folding edges for folding one of said pairs of side wall panels, brackets secured to said die bars and having downwardly offset portions bridging the space between said die bars, and folders mounted on said downwardly offset bracket portions and projecting from said brackets toward each other in a plane spaced downwardly from the plane of said die bars and constituting folders for engaging and folding the other pair of wall panels subsequent to the folding of the first pair thereof.

5. Apparatus for folding into carton form a blank having a bottom panel, two relatively angularly disposed pairs of side wall forming panels and end extensions on the free edges of one of said pairs of wall panels, comprising a die structure and a mandrel movable through said die structure to press said blank through the die structure, said die structure embodying a spaced pair of die bars providing an opposed pair of edges spaced apart a distance substantially corresponding to the distance across one pair of the carton side walls when folded to angular wall forming relationship to said bottom panel, said opposed edges constituting folding edges operative to fold one of said pairs of side wall panels, brackets secured to said die bars and having portions spaced downwardly therefrom bridging the space between said bars, folding blocks mounted on said downwardly spaced portions and having end portions projecting toward each other from said brackets and operative to engage and fold the second pair of side wall panels after the first pair is at least partially folded, and rotatable folders pivotally mounted on said brackets and located below the projecting portions of said folding blocks so as to permit the receptacle to be moved by said mandrel past said folding blocks and into the

space between the opposed pivoted folders, and means for rocking said folders through an arc of approximately 180° to fold said end extensions inwardly and downwardly over the inside of the last folded pair of walls.

6. In apparatus for folding into container form, a blank having a rectangular bottom panel, side wall-forming panels foldably connected to the edges of said bottom panel, and corner gussets connecting the adjacent ends of said side wall panels, the combination of a die, a mandrel movable through said die to pass a blank through said die, said die having one pair of oppositely disposed wall folding parts for effecting folding of oppositely disposed wall panels to container-forming position relative to said bottom panel as an incident to the movement of the mandrel and blank through said die, said wall folding parts having extensions which are operative to effect folding of said gusset portions in unison with the folding of said wall portions, means projecting from said extensions for engaging and buckling said corner gussets in the direction in which said walls are folded, and a second pair of oppositely disposed wall folding parts operative to fold the other pair of wall panels to container-forming position relative to said bottom panel as an incident to said movement of the mandrel and blank through said die but subsequent to the buckling of said gussets as aforesaid, whereby 30

said gussets are folded upon themselves and into face-to-face relation with the last folded wall as an incident to the folding of the latter, said mandrel having surface portions which cooperate with said second pair of wall folding parts to effect folding of said folded gussets upon themselves as aforesaid and to support said folded gussets for face-to-face engagement by the last folded walls as an incident to the folding thereof as aforesaid.

CHARLES E. PALMER.
